DESIGN FOR A JAR

Willis Burton Adams, Chicago, Ill., assignor to
Lysle E. Adams, trustee

Application November 29, 1935, Serial No. 59,823

Term of patent 14 years

To all whom it may concern:

Be it known that I, Willis Burton Adams, a citizen of the United States, residing at Chicago, in the county of Cook and State of Illinois, have invented a new, original, and ornamental Design for a Jar, of which the following is a specification, reference being had to the accompanying drawing, forming part thereof and wherein.

Fig. 1 is a front elevational view of a jar showing my design;

Fig. 2 is a side elevational view thereof; and
Fig. 3 is a top plan view thereof.

I claim:

The ornamental design for a jar, as shown.

WILLIS BURTON ADAMS.
